CLAIM

We claim the ornamental design for a refrigerator, as shown and described.

DESCRIPTION

FIG. 1 is a front perspective view of a refrigerator showing our new design, in which the shelf is in a folded state;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 2;

FIG. 9 is an exploded front perspective view thereof showing the shelf removed from the refrigerator;

FIG. 10 is enlarged view of the shelf in FIG. 9;

FIG. 11 is a front perspective view thereof;

FIG. 12 is a rear view thereof;

FIG. 13 is left-side view thereof;

FIG. 14 is a right-side view thereof;

FIG. 15 top view thereof;

FIG. 16 is a bottom view thereof;

FIG. 17 is a bottom perspective view thereof;

FIG. 18 is a front perspective view of the refrigerator in an alternate configuration, in which the shelf is in an unfolded state;

FIG. 19 is a front view thereof;

FIG. 20 is an enlarged view of the encircled portion in FIG. 19;

FIG. 21 is an exploded front perspective view thereof showing the shelf removed from the refrigerator;

FIG. 22 is enlarged view of the shelf in FIG. 21;

FIG. 23 is a front view thereof;

FIG. 24 is a rear view thereof;

FIG. 25 is a left-side view thereof;

FIG. 26 is a right-side view thereof;

FIG. 27 is a top view thereof;

FIG. 28 is a bottom view thereof; and,

FIG. 29 is a bottom perspective view thereof.

(Continued)

The evenly-dashed broken lines depict portions of the refrigerator that form no part of the claimed design. The dot-dot-dashed broken lines encircling portions of the claimed design that are illustrated in enlargements form no part of the claimed design.
